US00D924406S

(12) **United States Design Patent** (10) **Patent No.:** **US D924,406 S**
(45) **Date of Patent:** **** Jul. 6, 2021**

- (54) **ANALYTE SENSOR INSERTER**
(71) Applicant: **ABBOTT DIABETES CARE INC.**,
Alameda, CA (US)
(72) Inventors: **Phillip Yee**, San Francisco, CA (US);
Christopher A. Thomas, San Leandro,
CA (US); **Manuel L. Donnay**, San
Francisco, CA (US)
(73) Assignee: **ABBOTT DIABETES CARE INC.**,
Alameda, CA (US)
(**) Term: **15 Years**
(21) Appl. No.: **29/685,843**
(22) Filed: **Apr. 1, 2019**
